TYPEWRITER LINE SPACER

Ernest Lewis McMillan, Houston, Tex.

Application February 18, 1935, Serial No. 7,089

3 Claims. (Cl. 197—121)

My invention relates generally to means for controlling and predetermining the rotation of the platen of a typewriter through manipulation of the usual spacer handle, and particularly to means directly operated by the usual spacer handle whereby locked partial rotations of the platen may be achieved so as to predetermine the exact writing of lines spaced at intervals different both in point of location and in amount of spacing, from the usual spacings procurable on standard typewriters, such as single-space, double-space and triple-space, and an important object of my invention is to provide simple and inexpensive means of the character indicated above which may be readily and inexpensively adapted to different makes of standard typewriters and other typewriters and thereby greatly facilitate the work of the typist, particularly in filling in ruled-for-open forms, such as are extensively used in accounting, and thereby save considerable time besides increasing the accuracy and uniformity of the work.

Other objects and advantages of my invention will be apparent from a reading of the following description in connection with the drawings, wherein for purposes of illustration I have shown a preferred embodiment of my invention.

In the drawings:—

Figure 1 is a top plan view of a portion of a standard typewriter showing an application of the invention thereto.

Figure 2 is a transverse vertical sectional view taken through Figure 1 approximately on the line 2—2 and looking in the direction of the arrows.

Figure 3 is a front elevational view of Figure 1.

Figure 4 is a longitudinal vertical sectional view taken through a portion of the tab bar showing a portion of the invention connected thereto.

Figure 5 is a perspective view of the flexible supporting bracket.

Referring in detail to the drawings, the numeral 5 generally designates the platen of the typewriter with which is operatively engaged the clutch mechanism which is generally designated by the numeral 6, the connection of the clutch mechanism and the platen being controlled by the position varying knob 7, and the clutch releasing and engaging member 8, the latter having longitudinal movement and being normally outwardly sprung pressed in the clutch engaging position. At the rear of the typewriter is the usual tab bar 9 having the reduced threaded end 10. On the front of the typewriter is the usual link 11 having the pivot 12 which connects its front end operatively with the right angular arm 13 of the horizontally

reciprocable spacer lever 14 whereby pulling upon the free end of the lever 14 toward the right in the direction of the arrow will cause operation of the link 11 in a manner to rotate the platen 5 on its axis a distance equal to the number of line spaces for which the spacing mechanism generally designated 15 was set. These arrangements are conventional and vary slightly in different makes of typewriters but are in all general respects similar and do not require to be described herein for an understanding of the invention. In order to secure the greatest clarity in the explanation and illustration of the present invention, it may be pointed out that the drawings herein show adaptation of the invention to a standard "Royal" typewriter.

In accordance with the present invention a bracket which is generally designated 16, composed of the stationary generally horizontal bar 17 which has depending from its inner end the bifurcated portion 18 which is to engage behind the bolt 19, is to be clamped by the bolt in position on the typewriter. The bolt or screw 19 is already located on the lower part of the carriage of the typewriter. At the outer end of the bar 17 is a hinge 17' which is pivotally engaged with the lower end of the upright bar 20 whose upper end reaches approximately the level of the lever 13 where it is formed as a part of a universal connection 20' with the outer end of the generally horizontal bar 25 which is considerably shorter than the horizontal bar 17 and has on its inward end a depending pin 26 which is provided with a cotter pin receiving hole 27. The upright bar 20 is provided with a threaded hole 21. It should be pointed out that the bracket 16 is vertically and axially aligned with the axis of the platen 5 but located therebelow as is obvious in Figure 3.

Mounted in the opening 21 in the upright bar 20, the said opening being threaded, is the bolt or screw 22 which is provided on its outer end with the finger knob 23 and on its inner end with the head 24, the said screw 22 being axially aligned with the clutch operating member 8 as indicated in Figures 1 and 3. It is obvious that the hinge 17' and the universal connection 20' permit the upright 20 to be swung toward and away from the clutch operating member 8 so as to engage the head 24 of the screw 22 with the member 8 or to withdraw the screw from engagement with the member 8.

The operating linkage which is generally designated 29 is composed of the generally horizontal long bar 28 which has hinged as indicated at 28' to its front end the link 31 which has its

front end pivoted as indicated at 32 by the pivot 32 between the ears 33 of the clamp 34 which embraces the spacer lever 14 as indicated in Figure 2, the clamp being tightened by bolts or screws 35, as indicated in Figure 2. Near the front end of the bar 28 is provided a vertical opening which rotatably receives the pin 26 which depends therethrough and is prevented from working out therefrom by the cotter pin 30 as indicated in Figure 3.

10 At the rear end of the bar 28 is a hinge connection 29' to the axially outward end of the horizontal part of an inverted L-shaped member 36' whose standard portion 36 has on its lower end an axially inwardly extending horizontal part 37 which is provided with the reduced threaded part 38 which is threadedly received in the bore of the turnbuckle 39. The turnbuckle 39 replaces the usual nut found at this point on the standard typewriter. As shown in Figure 4 the threaded part 20 of the tab bar 9 passes through an opening in the carriage member 40 into the turnbuckle 39.

When it is desired to use the ordinary single-space, double-space, or triple-space on the typewriter platen action, the rod 22 is adjusted so that it does not in any position of the lever 14 engage the clutch operating member 8. When, however, it is desired to operate the spacer lever 14 in such a way as to shift the platen distances greater or less than the conventional spacing which would ordinarily be achieved by manipulation of the lever 14, the rod 22 is adjusted axially inward so as to strike the clutch operating member 8 at any predetermined stage of the movement of spacing lever 14. By reason of this provision for operating 35 the clutch operating member 8, ordinary operation of the spacing lever 14 will cause the clutch operating member to disengage the platen clutch at the predetermined point of the rotation of the platen 5. When the platen clutch is released, the 40 platen will then remain stationary at the point of release even though the spacing lever 14 is moved to the limit of its usual arc. By predetermining the adjustment of the rod or screw 22, the unconventional spacing may be exactly pre- 45 determined. It is obvious that the spring of the clutch operating member 8 and the spring of the spacer mechanism will throw the spacer lever 14 to the left and retract the rod 22 out of engagement with the clutch operating member 8, and 50 thereby reengage the clutch, so as to reengage the platen locking mechanism, whenever the lever 14 is released from a right hand position, so that the new spacing is as completely locked as the ordinary conventional spacing of the platen. This

feature of operation of the device of the invention eliminates the possibility in ordinary circumstances of ununiformly spaced and ununiformly written lines, and enables accurately and uniformly writing in oddly spaced lines such as "ruled-for-pen" forms have. 5

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. The combination with a typewriter carriage including a platen setting mechanism including a spacer lever, clutch means operatively engaged with the said mechanism, clutch releasing means, and third means operatively engageable with the 20 clutch releasing means and operable by said spacer lever so as to engage said clutch release means and release the clutch at any predetermined stage of actuation of the said mechanism for producing spacing rotation of the platen different from the 25 established spacing of the said mechanism, said third means being adjustable to vary its spacing effect.

2. The combination with a typewriter carriage including a tab bar, a platen, a platen setting 30 mechanism including a spacer lever, a clutch means operatively engaged with the said mechanism, clutch releasing means, and third means operatively engageable with the clutch releasing means and operable by said spacer lever so as to engage said clutch release means and release the clutch at any predetermined stage of actuation of the said mechanism for producing spacing rotation of the platen different from the established spacing of said mechanism, said third means being 40 adjustable to vary its spacing effect, and fourth means supporting the third means and connected to the tab bar of said carriage.

3. In a typewriter carriage including a platen, a spacer lever, and releasable clutch means for 45 said platen, clutch operating means for said clutch means, platen spacing means operated by said spacer lever, an adjustable member operable by said spacer lever and engageable with said clutch operating means in a manner to cause releasing of said clutch means at any predetermined stage of actuation of the platen spacing means.

ERNEST LEWIS McMILLAN.
